UNITED STATES PATENT OFFICE.

JACQUES LE GAUCLEAR, OF CHICAGO, ILLINOIS.

CONDENSER.

Application filed December 1, 1925. Serial No. 72,460.

This invention relates to variable electrical condensers, and particularly to condensers of this character, such as are used with radio receiving apparatus.

5 The objects of this invention are to provide an improved and efficient variable condenser; to provide a variable condenser which may be adjusted with great accuracy to improve its selective qualities and to 10 permit fine tuning; to provide a condenser of this character in which one set of plates are fixed and another set may be swung by means of a screw adjustment; to provide a condenser with an adjusting dial and an 15 indicating member which cooperates with said dial; and to provide such other unique features and improvements in construction as will be described more fully hereinafter. Certain features of my apparatus, and more 20 particularly the dial construction, which are shown and described herein but not claimed are claimed in my copending application for indicating dials, filed December 1, 1925, Serial No. 72,461.

25 In the accompanying drawings illustrating this invention:

Figure 1 is a longitudinal sectional view; Figure 2 is a bottom plan view of a portion of the condenser;

30 Figure 3 is a rear view of the dial casing with the parts removed to show the interior construction; and

Figure 4 is a fragment showing a portion of the dial and casing.

35 In the particular form of the invention as shown in these drawings, the frame 5 is formed of side plates 6 made of insulating material, and end cross bars or plates 7 and 8. The frame side members 6 have upwardly extending arms or projections 9 with cross-rods or bolts 10 on which one or more fixed plates 11 are mounted; these plates being held apart by spreaders or washers 12. These plates are connected by a conductor 45 13 with a binding post or screw 14.

The movable plates 15 are carried on a shaft 16 which is pivoted in the side members 6. Two links 17 are mounted on the shaft 16 and are connected at their outer 50 ends by a cross-bolt or pin 18 which also engages with the plates 15, these plates being held in adjusted position by washers or separators 19. The fixed and the movable plates are duplicates, all of such plates being

substantially circular with projecting ears 55 for engagement with the supporting bolts. The movable plates are connected by means of a conductor 46 with a binding post or screw 47.

The links 17 have downwardly projecting arms 20, having slots 21 therein which are engaged by a reciprocable cross bar 22, the ends of this bar engaging with slots 23 in the side plates. The cross bar 22 is rigidly secured to a nut 24 which is engaged by an adjusting screw 25. This screw may have either right or left hand threads, but preferably left hand, so that when it is turned in a clockwise manner, it will swing the plates together. The screw or threaded shaft 25 has a bearing 26 in the end cross piece 8 and is pointed at the opposite end as shown at 27 to form a pivot bearing for engagement with an adjustable bearing member 28 in the cross piece 7.

75 The shaft 25 is turned by means of a dial 29 which is connected with a knob 30.

The dial also coacts with an indicating member for indicating wave lengths, as more particularly shown in Figures 3 and 4. A casing 31 is secured to the panel 32 by means of screws 33 and is provided with an annular bearing for a rotatable indicating disk 34. This disk is provided with an internal gear 35 which is actuated by means of an oscillating eccentric lever 36, having teeth 37 at one end for engagement with the gear teeth and engaging at the opposite end with an eccentric 38 on the shaft 25. The eccentric lever has a slot 39 which engages with a pin 40 secured to the casing 31. The disk 34 is provided with a scale or numbers as indicated at 41 which are visible through an opening 42 in the casing. The dial 29 is also provided with a scale 43 which may be brought to register with a point or mark 44 on the casing.

80 When the knob or dial is turned to turn the shaft 25, the eccentric will cause the eccentric arm 36 to swing on the pivot 40 100 and move the disk one tooth for each complete revolution of the shaft, and the disk will be held in adjusted position by means of a double pawl or detent 45. The dial is preferably divided into sixty divisions and the indicating disk 34 is also preferably divided into 60 divisions and a complete revolution of the indicating member will 105

2
require sixty turns of the dial. The length of the arms 20 and the pitch of the screw 25 is also preferably arranged so that sixty turns of the dial will swing the adjustable plates from a position out of engagement with the fixed plates to a position in which they will coincide with the fixed plates, or in other words, to give a complete range of adjustment.

10 When the parts are proportioned in this manner, and are connected with other suitably arranged parts to make a receiving set, the indicating member 34 may be calibrated to indicate wave lengths so that the set may 15 be readily logged for different stations.

I have found that round plates are particularly efficient for use in condensers of this character and my adjusting mechanism provides means whereby such plates may be 20 moved or adjusted with the greatest accuracy in order to provide for fine or close tuning. Such advantages and other advantages will also be apparent to those familiar with this art and it will also be noted that changes 25 may be made in the size and proportion of the parts to adapt the device for different purposes and conditions and therefore I do not wish to be limited to the exact construction herein described, except as specified in 30 the following claims, in which I claim.

1. In a condenser, the combination of one or more fixed plates, one or more pivoted plates adapted to coact with said fixed plates, a screw, a nut engaging with the screw and 35 adapted to travel longitudinally thereon, and means for connecting the nut with the pivoted plates for swinging the same.

2. The combination of a frame having side members of insulating material, a series of 40 condenser plates mounted in said frame, a transverse shaft mounted in said frame, a series of plates mounted on said shaft and adapted to coact with the first named series, a threaded shaft mounted in said frame, a nut 45 on said shaft, means connecting the nut with the last named plates for swinging said plates, and means for turning said threaded shaft.

3. The combination of a frame, fixed 50 plates mounted in said frame, a transverse shaft in said frame, movable plates mounted on said shaft, arms projecting downwardly from said movable plates, a cross bar engaging with slots in said arm, said bar also engaging with slots in the frame, a nut on said 55 bar, a threaded shaft mounted in the frame

and engaging with said nut, and means for turning said shaft.

4. A condenser comprising a frame having sides formed of insulating material, fixed 60 plates mounted in said frame, a transverse shaft mounted in said frame, links secured to said shaft, plates secured to said shaft and links and adapted to coact with the fixed plates, arms projecting from said links, a screw mounted in said frame, a nut on said screw and a cross bar on said nut which engages with slots in said arms and with slots in the sides of the frame, the arrangement being such that when the screw is turned, 70 the cross bar will swing the plates on the transverse shaft.

5. A condenser comprising a frame having sides formed of insulating material, a series of round plates having outwardly projecting 75 ears, bolts engaging with said ears and said sides for holding plates in position, a transverse shaft mounted in said frame, links engaging with said shaft, a second series of round plates having projecting ears engaging 80 with said transverse shaft and with a cross bolt through said links, arms projecting outwardly from said links, a threaded shaft mounted in said frame and having an adjustable bearing at one end thereof, a nut 85 engaging with said shaft, a cross-piece on said nut which engages with slots in said arms, and is guided in the slots in the frame whereby, when the threaded shaft is turned, the links and connected plates will be swung 90 on the transverse shaft to adjust them with respect to the first named plates.

6. In a variable condenser, the combination of a support, fixed plates mounted in said support, movable plates pivotally mounted in the support adjacent to the fixed plates and adapted to coact therewith, a longitudinally movable cross head mounted in said support and adapted to coact with the movable plates for swinging the same, and means 100 for reciprocating said cross head.

7. In a condenser, the combination of a frame, a fixed plate mounted in said frame, a movable plate pivotally mounted in the frame adjacent to the fixed plate, a longitudinally movable cross head mounted in the frame, means for connecting the cross head with the movable plate for swinging the same, and means for reciprocating the cross head.

JACQUES LE GAUCLEAR.
